CLAIM

The ornamental design for a universal modular unmanned hybrid vehicle, as shown and described.

DESCRIPTION

FIG. 1.1 is a perspective view of a new design for a universal modular unmanned hybrid vehicle;
FIG. 1.2 is a front view of the universal modular unmanned hybrid vehicle of FIG. 1.1;
FIG. 1.3 is a left view of the universal modular unmanned hybrid vehicle of FIG. 1.1;
FIG. 1.4 is a right view of the universal modular unmanned hybrid vehicle of FIG. 1.1;
FIG. 1.5 is a back view of the universal modular unmanned hybrid vehicle of FIG. 1.1;
FIG. 1.6 is a top view of the universal modular unmanned hybrid vehicle of FIG. 1.1; and,
FIG. 1.7 is a bottom view of the universal modular unmanned hybrid vehicle of FIG. 1.1.
